(57) **CLAIM**

The ornamental design for a plate for fluid distribution pipe, as shown and described.

DESCRIPTION

FIG. 1 is a perspective view of a plate for fluid distribution pipe, showing my new design from the top, front and right side; and,

FIG. 2 is a perspective view thereof, from the bottom, rear and left side.

The view of the plate from the top, rear and left side is identical to FIG. 1.

The view of the plate from the bottom, front and right side is identical to FIG. 2.

The features shown in broken lines in FIG. 2 form no part of the claimed design.
